ABSTRACT OF THE DISCLOSURE

A driving mechanism for eliminating backlash having an output shaft with a flat surface thereon and a rocker arm having a center section with a flat surface engageable with the flat surface on the output shaft and first and second end sections of said rocker arm and first and second means for applying eccentric forces, respectively, to said first and second end sections thereby providing a torquing force to position said flat surface of said center section of said rocker arm in driving relation with said flat surface on said output shaft.

BACKGROUND OF THE INVENTION

The present invention relates to a driving mechanism and more particularly to a driving mechanism that eliminates backlash between a driven load and a driving system.

Various schemes and devices have, in the past, been employed to reduce or eliminate backlash in driving mechanism. Most frequently gear trains are employed and various devices have been used to eliminate backlash. One commonly employed antibacklash device is comprised of a first narrow width gear fixedly attached to a shaft, and a second narrow width gear rotatable on the same shaft and contiguous with the first gear. The first and second gears are resiliently biased together by means of pins and coil springs and are normally engaged with a third gear equal in width to the combined widths of the first and second gears. This commonly employed device, often called a split gear train, performs very satisfactorily in operation in reducing or eliminating backlash, but has a main disadvantage in that a large number of parts are required, some devices requiring as many as fifteen parts to make up a single assembly.

Another antibacklash device is shown and described in U.S. Pat. 2,868,033 which issued Jan. 13, 1959, to Raymond A. Gaither. This patented device provides a first spur gear integrally attached to a tubular shaft with a second spur gear having the same diametral pitch and the same number of teeth, integrally attached to a second shaft. The second shaft is positioned within the bore of the tubular shaft and the ends of these shafts opposite the ends the gears are attached are pinned together. The first spur gear is rotated relative to the second spur gear a distance equal to the width of one or more teeth prior to engaging a mating gear.

SUMMARY OF THE INVENTION

The present invention relates to a driving mechanism which does not have any gears and in which a driving member engages and can drive a driven member without any loss of motion. The driven member, which might be a shaft, is provided with a flat surface and a rocker arm is provided with a mating flat surface which engages the flat surface on the driven member. The rocker arm is provided with first and second end sections, and eccentric forces are applied to these end sections which provides a torquing force to keep the flat surface on the rocker arm in positive engagement with the flat surface on the driven member and also these eccentric forces

2

are utilized to rotate the driven member about its longitudinal axis.

It is therefore a general object of the present invention to provide a simple and relatively inexpensive device for driving a member in two directions, that is clockwise, or counterclockwise, without any loss of motion.

Other objects and advantages of the present invention will be readily appreciated as the same becomes better understood by reference to the following detailed description when considered in connection with the accompanying drawings.

BRIEF DESCRIPTION OF THE DRAWINGS

FIG. 1 is a top view of a rocker arm with push rods pivotally attached thereto and offset from the center of the rocker arm;

FIG. 2 is a front view of the rocker arm shown in FIG. 1 of the drawings;

FIG. 3 is a sectional view taken on line 3—3 of FIG. 2;

FIG. 4 is a sectional view showing a preferred embodiment of the present invention;

FIG. 5 is a partial side view of the preferred embodiment; and

FIG. 6 is a partial sectional view showing a driving and driven member.

DESCRIPTION OF THE PREFERRED EMBODIMENT

Referring first to FIGS. 4, 5, and 6 of the drawings, there is shown a housing 11 which is mounted in bearings 12 and 13 to provide alignment, and a concentric hole 14 is provided in housing 11. An output shaft 15 is rotatably mounted in hole 14, and a semicircular shaped tang 16 is provided on the inner end of shaft 15. As best shown in FIGS. 4 and 6 of the drawings, the semicircular shaped tang 16 provides a flat surface 17 on the inner end of output shaft 15. By way of example, output shaft 15 might have attached to its outer end, fins (not shown) which are utilized for controlling a missile.

A rocker arm 18, having a cylindrical section 19 and end sections 21 and 22, is provided in hole 23, which is bored perpendicular to hole 14. As best seen in FIGS. 1, 2, and 4, of the drawings, cylindrical section 19 has a pair of grooves 24 and 25 in the periphery, near each end, and O-rings 26 and 27 are positioned in grooves 24 and 25, respectively, to seal against moisture and dirt. Cylindrical section 19 of rocker arm 18 has a relief 28 thereby forming a flat surface 29 and, as best seen in FIG. 3 of the drawings, a tapered surface 31 is provided to determine the length of flat surface 29. Relief 28 is sufficiently wide to accommodate tang 16, and as best shown in FIGS. 4 and 6 of the drawings, flat surface 17 of tang 16 engages flat surface 29 on cylindrical section 19.

End sections 21 and 22 are provided with yokes 32 and 33, respectively, and push rods 34 and 35 are pivotally attached to yokes 32 and 33, respectively, by pins 36. Bearings 37 and 38 are provided to facilitate pivoting. As best seen in FIGS. 1 and 5 of the drawings, the center line 41 of cylindrical section 19 is offset a distance d from the center line 42 of push rods 34 and 35. Push rods 34 and 35 are actuated by hydraulic linear actuators 43 and 44, respectively.

The engagement of push rods 34 and 35 with yokes 32 and 33, respectively, is such that forces are applied which perform two functions. Push rods 34 and 35 provide the force necessary to position output shaft 15 and in addition, forces are applied which remove all backlash between rocker arm 18, the driver, and shaft 15, the driven element. The forces are applied at points eccentric to the center axis of rocker arm 18, the offset being distance d , and this offset causes rocker arm 18 to be rotated about its center so that the flat surface 29

of cylindrical section 19 engages the flat surface 17 on tang 16 of output shaft 15. Driving forces are transmitted through the flat surface engagement. This engagement force is always the sum of the two forces applied by the push rods and effectively removes all backlash.

It can thus be seen from the foregoing description that the present invention utilizes a driving force to perform a second function of removing backlash. There is no development of backlash due to wear as the mechanism will automatically adjust itself. The present invention provides for the indexing of an output shaft, with its load, by the simple and inexpensive expedient of machining a flat surface on the end of a shaft.

I claim:

1. An ant backlash device comprising:
a housing,
an output shaft rotatably positioned in said housing and having a flat surface on one end thereof,
a rocker arm having first and second forked end sections and a cylindrical center section having a relief therein extending to the longitudinal axis thereof thereby providing a flat diametrical surface engageable with said flat surface on said output shaft, the centers of said forked end sections being offset from the longitudinal axis of said cylindrical center section, and
first and second means for applying forces, respectively, to said first and second forked end sections

whereby a torquing force is developed to position said flat surface of said center section of said rocker arm in driving relation with said flat surface on said output shaft and whereby said first and second means selectively apply forces for pivoting said rocker arm thereby turning said output shaft.

2. An ant backlash device as set forth in claim 1 wherein said cylindrical center section has a tapered surface conterminous with said flat surface whereby the length of said flat surface is less than the diameter of said cylindrical center section.

3. A zero backlash device as set forth in claim 4 wherein said first and second means comprises piston-actuated push rods pivotally connected one each to said first and second forked end sections.

UNITED STATES PATENT OFFICE
CERTIFICATE OF CORRECTION
UNDER RULE 322

Patent No. 3,557,630 Dated January 26, 1971

Inventor(s) R. J. ESTLICK

It is certified that error appears in the above-identified patent and that said Letters Patent are hereby corrected as shown below:

Column 4, Claim 2, change:

"An antibacklash device as set forth in claim 4"

To read:

An antibacklash device as set forth in claim 1

Column 4, Claim 3, change:

"A zero backlash device as set forth in claim 4"

To read:

A zero backlash device as set forth in claim 1

Signed and sealed this 2nd day of November 1971.
